UNITED STATES PATENT OFFICE.

WALTER R. KAHNS, OF CHICAGO, ILLINOIS, ASSIGNOR TO J. H. WHITE MANUFACTURING COMPANY, OF BROOKLYN, NEW YORK, A CORPORATION OF NEW YORK.

LIGHTING-FIXTURE.

1,176,459.

Specification of Letters Patent. Patented Mar. 21, 1916.

Application filed August 12, 1915. Serial No. 45,099.

To all whom it may concern:

Be it known that I, WALTER R. KAHNS, a citizen of the United States, and resident of Chicago, in the county of Cook and State of Illinois, have invented an Improvement in Lighting-Fixtures, of which the following is a specification.

My present invention relates to that class of electric lighting fixtures giving a candle effect, in which a hollow cylinder is employed to represent the candle. In fixtures of this character, it is customary to mount the lamp in a socket supported in the upper end of the hollow cylinder. In such cases frosted ball lamps are generally employed in consequence of the glare and lack of distribution of light where a clear glass is employed.

One of the objects of my invention is to provide a shade holder for candle fixtures, whereby a clear Mazda lamp with standard glassware may be used, diffusing and distributing the light in a pleasing and efficient manner, thus combining ornamental appearance with practicability; and a further object of the invention is to dispense with the additional support for the lamp socket by making the cylinder representing the candle of such size and character as to cover a standard key socket, and at the same time support the shade holder. This construction of candle cylinder does away with the requirement heretofore necessary of putting a switch either in the bracket or candle cup.

The details of the invention are hereinafter particularly described.

In the accompanying drawing: Figure 1 is a sectional elevation illustrating my invention. Fig. 2 is an elevation of the candle cylinder detached. Fig. 3 is an elevation of the cup detached, and Fig. 4 is an elevation of the shade-ring detached, its projecting arms being broken away.

Similar reference characters indicate the same parts throughout the several views.

10 indicates a pipe which is connected to a chandelier, wall bracket or other lighting fixture. The free end of this pipe is provided with an exteriorly screw-threaded hollow stud 11.

13 designates a metallic cup having a central opening in its bottom, and fitted over the stud 11 within the shell 12. This cup has an annular concave rim 14 and interior

16 indicates a somewhat elongated hollow cylinder representing a candle. This cylinder is provided with a slot 17, extending vertically from its lower edge a predetermined distance.

18 denotes a standard key lamp-socket provided with the usual interiorly screw-threaded stud at its bottom which is screwed down upon the stud 11 of the pipe 10, over the cup and shell, thus securely holding these parts in place. The key 19 of the lamp socket 18 extends through the slot 17 in the candle cylinder 16, so that it may be manipulated without disturbing said cylinder.

20 indicates a ring of a size adapted to fit snugly within the top of the candle cylinder 16, and it is provided with a flange 21 at the top edge, which flange rests upon the top of the candle cylinder when the ring is inserted therein.

22, 22 are two oppositely disposed arms, the lower ends of which are attached to the ring 20 on its inner surface. These arms may be secured to the ring by rivets 23, or by solder, or in any other suitable manner. The arms 22 extend upwardly, preferably in a slightly oppositely bowed form, and at their upper ends are secured to a dome 24. Extending upwardly from the top of the dome 24 is a screw-threaded projection 25.

26 denotes a shade which is placed over the dome 24, with its contracted upper portion resting upon the flared lower portion of said dome.

27 indicates a cap with a central opening in its top of a size to permit the passage of the screw-threaded projection 25 therethrough, so that the cap may be placed over the dome and rest upon its top. The lower portion of the cap covers the extreme upper portion of the shade 26, while the bottom edge of the cap preferably contacts with the outer surface of the shade which gives a finished and ornamental appearance. After the shade and cap have been placed in position, an ornamental nut 28 is screwed upon the projection 25, into contact with the top of the cap, thereby holding the cap and shade in their proper positions, and preventing the removal of either without first unscrewing said nut.

29 indicates an incandescent electric lamp. The conductor wires 30 pass through the pipe 10.

By the employment of my invention, sev-

eral objectionable features heretofore found in lighting fixtures giving a candle effect are overcome, as no additional support for the lamp socket is required; the standard key 5 socket may be made use of; the cylinder representing the candle acts as a cover for such socket and permits the manipulation of the key without disturbing any of the parts; the candle cylinder also acts as a support for a 10 shade ring, whereby a shade may be used in connection with the candle fixture, rendering it unnecessary to employ frosted ball lamps, and providing for the employment of clear Mazda lamps with standard glassware, and 15 diffusing and distributing the light in a pleasing and efficient manner.

I claim as my invention:

1. In a lighting fixture, the combination of a supporting tube provided on its free-end 20 with a screw threaded stud, a cup fitted over said stud and provided at its top with a concave annular rim and internal annular shoulder at the base thereof, a lamp socket screwed upon said stud and clamping said cup in 25 place, an elongated cylinder surrounding said socket with its lower end inserted in said annular rim of said cup and resting upon said shoulder in said cup, a ring fitting into the upper part of said cylinder and provided 30 with a flange resting upon the top of said cylinder, arms secured at their lower ends to the interior of said ring and extend-

ing upwardly therefrom, a dome to which the upper ends of said arms are secured, a shade supported upon said dome, and a cap 35 covering the said dome and the upper portion of said shade.

2. In a lighting fixture, the combination of a supporting tube provided on its free end with a screw threaded stud, a cup fitted over 40 said stud and provided at its top with a concave annular rim and internal annular shoulder at the base thereof, a lamp socket provided with a key screwed upon said stud and clamping said cup in place, a cylinder surrounding said socket and having a slot in one side through which said socket key extends, the lower end of said cylinder being inserted 45 in said annular rim and resting upon said shoulder in said cup, a ring fitting into the 50 upper part of said cylinder and provided with a flange resting upon the top of said cylinder, arms secured at their lower ends to said ring and extending upwardly therefrom, a dome to which the upper ends of 55 said arms are secured, a screw threaded projection extending from the top of said dome, a shade supported upon said dome, a cap covering said dome and the upper portion of said shade, and a nut screwed upon the said 60 screw threaded projection.

Signed by me this 14th day of July, 1915.

WALTER R. KAHNS.
